CLAIM

The ornamental design for a dual compartment sandwich package, substantially as shown and described.

DESCRIPTION

FIG. 1 is a perspective view of a dual compartment sandwich package showing our new design;

FIG. 2 is a top plan view thereof;

FIG. 3 is a side elevational view thereof, the opposite side being the same in appearance;

FIG. 4 is an end elevational view thereof;

FIG. 5 is an elevational view showing the end opposite that seen in FIG. 4;

FIG. 6 is a bottom plan view thereof;

FIG. 7 is a top perspective view showing a modified form of our new design;

FIG. 8 is a top plan view thereof;

FIG. 9 is a side elevational view thereof, the opposite side being the same in appearance;

FIG. 10 is an end elevational view thereof;

FIG. 11 is an end elevational view showing the end opposite that seen in FIG. 10; and

FIG. 12 is a bottom plan view thereof.
